PORTABLE PENCIL SHARPENER

Ira S. Peightel, Harrisburg, Pa.

Application April 22, 1946, Serial No. 663,919

3 Claims. (Cl. 120—96)

1

The invention relates to a pencil sharpener, and more especially to a portable hand supported pencil sharpener.

The primary object of the invention is the provision of a sharpener of this character, wherein by use of a pair of milling cutters of the roller type, ball bearings and an automatic centering and feed control a pencil will be automatically held and fed to the cutters, which latter are manually actuated for the sharpening of the said pencil, the sharpener being self-contained, and it is of novel construction and unique in the assembly of the parts thereof which are few in number.

Another object of the invention is the provision of a sharpener of this character, wherein a novel form of pencil feeding and gripping action is involved, self-contained in a case, which may be of unlimited design and constructed from plastic materials, chrome plated brass or silver finish or enamel, the cuttings being held within the case until discharged therefrom, and the sharpener as a whole usable as a paper weight, and at all times handy for service as a sharpener.

A further object of the invention is the provision of a sharpener of this character, wherein it is automatic in centering, feeding and the holding of a pencil therein during the sharpening operation, thus eliminating the manual holding and feeding of the pencil during the sharpening period, the centering, feeding and holding assembly being wholly confined within the case of the sharpener.

A still further object of the invention is the provision of a sharpener of this character, which is simple in construction, thoroughly reliable and efficient in operation, strong, durable, readily and easily operated, portable, compact, neat in appearance, and inexpensive in manufacture.

With these and other objects in view, the invention consists in the features of construction, combination and arrangement of parts as will be hereinafter described, illustrated in the accompanying drawings, which disclose the preferred embodiment of the invention and pointed out in the claims hereunto appended.

In the accompanying drawings:

Figure 1 is a side elevation of the sharpener constructed in accordance with the invention;

Figure 2 is a sectional view taken on the line 2—2 of Figure 1 looking in the direction of the arrows;

Figure 3 is a sectional view taken on the line 3—3 of Figure 2 looking in the direction of the arrows.

2

Figure 4 is a sectional view taken on the line 4—4 of Figure 2 looking in the direction of the arrows;

Figure 5 is a sectional view taken on the line 5—5 of Figure 2 looking in the direction of the arrows but showing the device in position to receive a pencil;

Figure 6 is a sectional view taken on the line 6—6 of Figure 2 looking in the direction of the arrows;

Figure 7 is a perspective view of one spring retainer clip;

Figure 8 is a perspective view of the feeder follower of the pencil clamp.

Similar reference characters indicate corresponding parts throughout the several views in the drawings.

Referring to the drawings, the pencil sharpener constituting the present invention, comprises a two part cylindrical casing denoted generally at A, having the aligned parts 10 and 11 respectively, which are closed permanently at their ends, while the inner meeting ends are fully open to each other, and in this aligned condition are movable relative to one another. Within each part 10 and 11 is a cylindrical shell 12 and 12', respectively, and the shell 12 within the part 10 being fixed thereto in any suitable manner when installed therein. The part 11 is removably fitted onto the shell 12' therein and these are frictionally held together when interfitted with each other. In the part 11 is arranged a cutting mechanism, that is to say, the rotary roller-like cutting wheels 13, which are located diametrically opposite each other, and are disposed eccentrically about a pencil guide 14 centered thereto, and converge away from the latter. The guide 14 has oppositely extending arms 15 which with a pair of arms 16 form a cage for the cutters 13 in a manner to appear. The fitting 15 of the cage forms a bearing for the axles 17 of the cutters 13 (see Fig. 3), and this guide 14 is made fast by tie rods 18 (see Fig. 2) of such cage to a rotatable sleeve 19, within the shell 12 in the part 10, the said shell 12 and sleeve 19 being formed with an annular ball bearing raceway 20, having therein the bearing balls 21 and in this manner the parts 10 and 11 through their respective shells 12 and 12' are held coupled together for rotation with respect to each other.

The cutters 13 at their axles 17 are fitted with toothed gears 22, which mesh with an internally toothed driving ring-like gear 23, which is peripherally fixed within the open end of the shell 12 within the part 10, so that by turning

the latter relative to the part 11, the cutters will rotate for the cutting or sharpening of a pencil, not shown, when inserted within the guide 14 through a clearance therefor as at 24 in the outer end of the part 10 as best seen in Figures 1 to 3 inclusive of the drawings.

Within the shell 12 in the part 10 of the casing A, there is arranged a pencil gripping feeder mechanism, which involves a feeder follower disk 25, Fig. 8, having a center clearance opening 25' aligned with the guide 14 for the pencil, and this disk 25 at its periphery has a mutilated rim 26, forming diametrically opposed cutaway areas 27 through which are exposed the outer ends of interfitted gripping frames 28 laterally biased by springs 29' and having at their inner ends gripping jaws 29, opposed to each other and inter-fitted for embracing the pencil, when inserted in the guide 14, for holding it until released by such jaws, in a manner hereinafter described.

The frames 28 have connected thereto outwardly bowed springy spreader leaves 30, with which engage actuator dogs 31 reversely pivoted at 32 to the disk 25, and such dogs at their reverse ends 33 extend through openings 31' and work within respective half spiral camming grooves 34 disposed opposite each other within the sleeve 19, which is turnable in the shell 12 in the part 10 and in this manner the jaws 29 are brought into gripping engagement with the pencil for the holding thereof in sharpening position. Each groove 34, as shown in Figure 3, has one of its side walls 34' perpendicular to its bottom and its opposite wall 34" inclined thereto. A cover plate 35' fits within the disk 25, Fig. 2, to retain the frames 28 in position.

The disk 25 is advanced or fed in the direction of the guide 14 under the action of tensioning springs 35, which are carried on hanger arms or rods 36 supported from a stationary bracket 37, which is secured in the shell 12 in the part 10, next to its outer closed end, while the frames 28 at their outer exposed ends are adapted to play against releasing cams 38, see Figs. 3 and 5, provided in the sleeve 19 and at diametrically opposite area thereof. This play of the frames 28 takes place when the sleeve 19 is turned clockwise, as viewed in Figs. 4 and 5, as a result of which the jaws 29 will release the pencil. Turning the sleeve 19 in a counter-clockwise direction, as viewed in Figs. 4 and 5, will cause the pencil to be sharpened by the cutters 13.

The cuttings or shavings from the pencil when sharpened will be trapped in the part 11, which on removal thereof from its shell 12' permits dumping of such cuttings or shavings out of the sharpener, as will be obvious.

Thus, assuming the frames 28 are against the releasing cams 38, Fig. 5, the jaws 29 are thus separated preparatory to receiving a pencil. After inserting a pencil, the operator turns the shell 12 in a clockwise direction relative to shell 12', as viewed in Fig. 5, causing the frames 28 to ride off the cams 38 and grip the pencil through jaws 29. Continued rotation of shell 12 will cause the ends 33 of the dogs 31 to ride down the grooves 34, moving the disk 25 toward the guide 14 assisted by the springs 35, compressed from a previous cycle of operation. Movement of the disk 25 toward the guide 14 advances the pencil through the cutting wheels 13. In the event the action of the grooves 34 and ends 33 tends to feed the pencil more rapidly than it is cut by the wheels 13, the force exerted by the spreader leaves 30 will be overcome and the ends

33 will ride out of the grooves 34 by passing over the inclined surface 34". With the ends 33 out of their respective grooves 34, the springs 35 will continue to move the disk 25 toward the guide 14 feeding the pencil into the cutters 13. To withdraw the pencil from between the cutters, the direction of rotation of shell 12 relative to shell 12' is reversed. That is, shell 12, viewing Fig. 2, is turned toward the observer (counter-clockwise in Fig. 4) causing the ends 33 to ride in the grooves 34 and bearing against the perpendicular sides 34'. This in turn results in the disk 25 being rotated and withdrawn to the top of the sharpener, compressing springs 35. When the disk 25 reaches the top, or end of shell 12, the ends 33 approach the end of their respective grooves, at which time the frames 28 contact the cams 38, Fig. 5, to cause separation of the jaws 29 to release the pencil.

20 What is claimed is:

1. In a pencil sharpener having a frame structure, cutting rollers carried thereby and driving means for rotating said rollers, the combination therewith of an automatic pencil holding and feeding device for advancing a pencil toward the cutting rollers, said device comprising a shell secured to the driving means, a sleeve secured to the frame structure, helical grooves in said sleeve and each of said grooves having a wall normal to the base of the groove and a wall inclined to the groove base, disk means rotatably and reciprocably mounted in said sleeve, opposed gripping means slidably carried by said disk means and adapted to grip a pencil, dogs pivoted on said disk means and adapted to engage said grooves, respectively, compression means secured to said shell and drivingly connected to said disk means whereby rotation of the shell in one direction will rotate said disk means and whereby said compression means will advance said disk means toward the cutting rollers, the said walls inclined to the base of the grooves allowing said dogs to be moved out of said respective grooves whereby said disk means may be advanced toward the cutting rollers independently of said grooves, said dogs being adapted to engage the walls normal to the base of said respective grooves for moving said disk means away from the cutting rollers upon rotation of the shell in a direction opposite to said one direction, and cam means on said sleeve adapted to engage said gripping means for causing the same to release the pencil for removal therefrom.

2. In a pencil sharpener having a frame structure, cutting rollers carried thereby and driving means for rotating said rollers, the combination therewith of an automatic pencil holding and feeding device for advancing a pencil toward the cutting rollers, said device comprising a shell secured to the driving means, a sleeve secured to the frame structure, disk means rotatably and reciprocably mounted in said sleeve, opposed gripping means slidably carried by said disk means and adapted to grip a pencil, compression means secured to said shell and drivingly connected to said disk means whereby rotation of the shell in one direction will rotate said disk means and whereby said compression means will advance said disk means toward the cutting rollers, means between said sleeve and disk means for withdrawing said disk means away from the cutting rollers upon rotation of the shell in a direction opposite to said one direction.

3. In a pencil sharpener having a frame structure, cutting rollers carried thereby and driving

means for rotating said rollers, the combination therewith of an automatic pencil holding and feeding device for advancing a pencil toward the cutting rollers, said device comprising a shell secured to the driving means, a sleeve secured to the frame structure, disk means rotably and reciprocably mounted in said sleeve, opposed gripping means slidably carried by said disk means and adapted to grip a pencil, compression means secured to said shell and drivingly connected to said disk means and whereby rotation of the shell in one direction will rotate said disk means and whereby said compression means will advance said disk means toward the cutting rollers, means for moving said disk means away from the cutting rollers upon rotation of the shell in a direction opposite to said one direction, and cam means on said sleeve adapted to engage said

gripping means for causing the same to release the pencil for removal therefrom.
